UNITED STATES PATENT OFFICE.

ELZA R. STEALY, OF SHENANDOAH, IOWA.

DENTAL APPLIANCE.

1,119,373.

Specification of Letters Patent.

Patented Dec. 1, 1914.

Application filed February 28, 1911. Serial No. 611,468.

To all whom it may concern:

Be it known that I, ELZA R. STEALY, citizen of the United States, residing at Shenandoah, in the county of Page and State of Iowa, have invented certain new and useful Improvements in Dental Appliances, of which the following is a specification.

My invention relates to dental apparatus and more particularly to apparatus primarily designed for dental casting.

The invention relates to the investment cups and flasks within which the casting is made.

The primary object of my invention is to provide means whereby the investment material disposed within an investment cup may be submitted over a large portion of its surface to the action of a vacuum (if a vacuum is being used for casting) and in connection therewith to provide investment rings or flasks, each having an air-tight engagement with the investment cup but so constructed as to present a relatively large surface to the action of the vacuum.

A further object is to improve the construction of the investment cup and the investment ring or flask, so as to permit the cup and flask to be used in many different ways for different forms of casting.

My invention is illustrated in the accompanying drawings wherein:

Figure 1 is a longitudinal diametrical section through an investment cup, this figure showing the investment therein. Fig. 2 is a like section to Fig. 1, but showing the investment placed within an investment ring. Fig. 3 is a like view to Fig. 2 but showing another manner of engaging the investment ring or flask with the investment cup. Fig. 4 is a longitudinal diametrical section of a flask or investment ring. Fig. 5 is a like view to Fig. 4 but showing another form of investment ring or flask. Fig. 6 is a longitudinal diametrical section of an investment cup, a supplemental ring and an investment ring or flask, this having the form of the ring shown in Fig. 4.

My improved investment cups are intended to be used with a vacuum chamber to which the cups are connected by means of a connecting tube in a manner so well known in the art as not to need further description, and the details of the vacuum apparatus need not be stated as vacuum chambers for this purpose are also well known in the art and my investment cup and ring or flask

may be used with any desired vacuum chamber.

For the purpose of supporting the investment in proper relation to the vacuum apparatus, I provide an investment cup 17, such as that illustrated in Fig. 1. This investment cup is either round or oval, the round cup being used for casting relatively small articles. The cup is provided with a slightly tapering body, the internal surface of which is ground or otherwise formed so as to provide an air-tight joint with an investment ring to be later described. The external surface of the cup is also ground, for a purpose to be later described.

The lower end of the cup is formed with a tapering stem 18. The bore of this stem is preferably tapered reversely to the exterior of the stem, that is, it contracts in diameter from the end of the stem toward the body of the cup, and the interior face of the bore is ground. The exterior face of the stem is also ground so that the stem may be inserted within the tapering end 13 of a tube 9 and will form an air-tight ground joint therewith. This tube 9 connects to a vacuum chamber, not shown. The bottom of the investment cup surrounding the central bore of the stem is flat as at 18^a and ground so as to form an air-tight joint with the ground bottom of an investment ring, as will be later described.

As a means for supporting the investment within the investment cup and permitting the investment to be readily inserted or withdrawn therefrom, and further to permit the investment to be submitted to the action of the vacuum over a relatively large surface, I provide an investment ring such as shown in Figs. 2 to 6 and designated 23 in Fig. 2 and 23^a in Fig. 3. This ring or flask has a slightly tapering body portion adapted to fit snugly in the interior of the investment cup, the outer face of the body portion being ground where it contacts with the inner face of the investment cup so as to form an air-tight joint therewith. The bottom of the investment ring or flask in the form of investment ring shown in Figs. 2 and 3 is formed with an annular seat and has a central depressed portion formed with a central opening 22 in Fig. 2 or openings 22^a in Fig. 3.

In Fig. 2 the investment ring or flask 23 is of such size relative to the investment cup that it will fit within the upper por-

tion of the investment cup, but will not extend to the bottom of the cup, so that an air space is left between the bottom of the cup and the bottom of the investment ring. 5 The exterior face of the investment ring 23 is ground so as to form an air-tight joint with the ground interior face of the cup 17.

As shown in Fig. 3, the investment ring is formed with a relatively flat annular margin 24^a which is ground upon its exterior face so as to rest upon the ground bottom 18^a of the investment cup 17^a and form an air-tight joint therewith. This permits an investment ring 23^a to be used with an investment cup considerably larger than the diameter of the investment ring as shown in Fig. 3. The ring in that case rests upon the bottom of the investment cup and makes an air-tight joint therewith. The sides of 15 the investment ring shown in Fig. 2 are imperforate, and this imperforate investment ring is preferably used for casting bridges or other relatively large castings, as there is no danger in using this ring, of placing 20 the end of the wax form too near the perforations in the side of the ring as there would be were the investment of such castings made in the rings shown in Figs. 4, 25 5 and 6, to be later described.

30 In Fig. 4 I show another form of an investment ring, so designed as to provide an increased area for the action of the vacuum upon the investment material. In this form of the invention the investment cup 30^a is provided with a plurality of vertical slots 31 terminating at their upper ends in enlarged openings 32. It will be seen that when this ring is placed within the cup as in Fig. 6, the slots 31 opening as they do at 35 40 the bottom of the ring and extending upward as they do along the outer face of the investing material, will provide for the withdrawal of air through the side of the investing material as well as through the bottom thereof. In this form of ring 45 the bottom is perforated.

In Fig. 5 I show still another form of investment ring embodying my invention and very similar to the ring shown in Fig. 4. The wall of the investment ring 30^b near 50 its lower end is provided with a plurality of perforations 33 which connect with the vertically disposed grooves 34 extending down on the exterior face of the wall of 55 the investment ring and opening at the lower end thereof. It will be obvious that this form of investment ring when placed within an investment cup will afford a plurality of peripheral passages between the 60 outer face of the ring and the inner face of the investment cup by which air may be withdrawn from around the side of the investing material as well as through the lower end thereof. I have found in practice that the two forms of investment rings 65

shown in Figs. 4 and 5 are particularly effective.

In Fig. 6 I show a number of investment rings supported one inside of another within an investment cup, thus providing means whereby a relatively small investment ring may be used with a relatively large investment cup. It will be seen that this manner of using the investment rings is rendered possible by the exterior and interior faces of the investment rings being ground and by the fact that the interior face of the investment cup is ground.

70 In Fig. 6, 17 designates the investment cup of the form heretofore described, 38 an investment ring preferably formed without a bottom, and 30^a designates a relatively small investment ring such as that shown 75 in Fig. 4 supported in the first named investment ring.

In Fig. 1 the investment cup is shown as filled with investment material. Before the investment material in its plastic form is placed within the cup, a slip of paper 25 is disposed over the opening of the cup, this 80 slip being afterward burned away. In Figs. 2 and 3 the investing material is shown as being disposed within the investment rings or flasks. The process of investing the casting is well known and therefore 85 requires no special description. It is pointed out, however, that the investment material after it hardens being porous and the area of the surface for the vacuum being relatively large, the molten metal will 90 be drawn immediately into the cavity left by the inlay or pattern and forced into every portion of said cavity, thus securing an accurate and effective reproduction in metal 95 of the pattern.

100 The process of casting is particularly well carried out by the form of cups shown in Figs. 4, 5 and 6 as here the side of the investment is subjected to the action of the vacuum as well as the bottom by reason of 105 the slots or grooves and the perforations in the side walls of the investment flask or ring.

110 Having thus described the invention what is claimed as new is:—

1. A dental appliance of the character 115 described, including a receptacle consisting of a bowl-shaped body having a tapering stem, the exterior and interior of the stem being ground, and the interior face of the body being ground.

120 2. A dental appliance of the character described, including a receptacle consisting of a bowl-shaped body having an exteriorly tapering stem, the interior of the stem being reversely tapered to the exterior thereof, the exterior and interior faces of the stem being ground.

125 3. A dental appliance of the character described, including a receptacle comprising a bowl-shaped body having a tapering tubu- 130

- lar stem, the bottom of the interior of the bowl-shaped body being flat and ground.
4. In a dental appliance, the combination with a receptacle comprising a bowl-shaped body having a tapering tubular stem, the bottom of the interior of the bowl-shaped body being flat, of a ring for use therewith insertible within the body, the bottom of the ring having an opening, that portion of 10 the ring surrounding the opening being flat and ground upon its face to form an air-tight joint with the bottom of the body:
5. A dental casting apparatus including a hollow body opening at opposite ends, and 15 a flask contained within the hollow body and having an air-tight engagement therewith, the lower end of the flask being formed with longitudinally extending cutaway portions opening at the lower end of the flask.
- 20 6. A dental casting appliance, a hollow body open at opposite ends, and a flask contained within the hollow body, the exterior face of the flask having an air-tight joint with the interior face of the hollow body, 25 one end of the flask being formed with lon-
- gitudinally extending grooves opening at the bottom of the flask.
7. A dental casting appliance, a hollow body open at opposite ends, and a flask contained within the hollow body, the exterior 30 face of the flask having an air-tight engagement with the interior face of the hollow body, the exterior face of the flask at one end being longitudinally grooved, said grooves terminating in perforations, extend- 35 ing into the internal face of the flask.
8. A flask for dental investments comprising a tapering annular body and formed adjacent one end with longitudinally extending passages, each opening at one end 40 at the end of the flask, the other end of each passage communicating with a radially extending perforation in the flask wall.

In testimony whereof, I affix my signature in presence of two witnesses.
